UNITED STATES PATENT OFFICE.

FRANK R. MCBERTY, OF ANTWERP, BELGIUM, ASSIGNOR TO WESTERN ELECTRIC COMPANY, OF NEW YORK, N. Y., A CORPORATION OF ILLINOIS.

AUTOMATIC TELEPHONE-EXCHANGE SYSTEM.

1,124,314.

Specification of Letters Patent.

Patented Jan. 12, 1915.

Application filed June 3, 1913. Serial No. 771,469.

To all whom it may concern:

- Be it known that I, FRANK R. MCBERTY, a citizen of the United States, residing at Antwerp, in the province of Antwerp and Kingdom of Belgium, have invented a certain new and useful Improvement in Automatic Telephone-Exchange Systems, of which the following is a full, clear, concise, and exact description.
10. This invention relates to an improvement in automatic and semi-automatic telephone systems and refers more particularly to an improved arrangement of circuits by virtue of which the speed at which a given 15 connection may be made is increased and the general operation of the connecting apparatus improved.

The invention is particularly applicable to automatic or semiautomatic systems in which a selector switch is governed in its movement by a sending device which in turn is governed in its movement by electrical impulses caused by the movement of the selector switch, the arrangement being 25 such that the sending device is displaced from normal position to a predetermined position, depending upon the terminal it is desired to select, and is stepped back to normal by impulses produced by an interrupter 30 associated with the selector switch. Such systems of control are well known in the art and are designated as systems employing the revertive impulse control.

It has been found that in systems of revertive impulse control the speed at which a connection may be made depends upon the speed at which the controlling magnets at the sending device and selector switch may be made to respond. It has also been found 35 that such magnets will respond with greater rapidity to impulses formed by breaking of a circuit than to impulses formed by diverting or shunting a part of the current. Therefore, in order to obtain the maximum speed in the invention hereinafter disclosed, the controlling magnets of the sending device and selector are connected in series in a circuit which is opened and closed by an interrupter associated with the selector switch. 40 In order that the selector switch may be more positively controlled and its operation rendered more certain, provision is made for electrically controlling said selector during the time that the main controlling circuit 45 referred to above is interrupted.

The invention is shown in the accompanying drawing which is a diagrammatic representation of the system.

The sender may be of any well known type in which a stepping magnet is used to step a dial or arm to a predetermined point, and in which means are provided to operate a stop relay or the equivalent upon the arrival of the sender arm at such point. The sending device is not illustrated on the drawing as its construction and operation are well known. The ordinary stepping magnet of a sender, however, is shown at 67 and the stop relay at 68. Obviously, the sending device may be located either at the subscriber's substation or at the central office, the operation being the same.

The selector or connector switch, which is employed in the specific embodiment of the invention shown on the drawing, is substantially the same as that disclosed in the applicant's British Patent No. 16,867 of 1911 to which reference may be had for a more complete description. The essential parts of such a selector switch are shown 50 diagrammatically on the drawings in which 75 represents a constantly rotating shaft, 6 and 7 magnetic disks secured thereto and rotating therewith. Cooperating with the disks 6 and 7, and at right-angles thereto, 85 are the disks 59 and 8. The disks 7 and 59 are flexibly mounted so that they may be drawn into engagement with the disks 6 and 8 when the solenoids 14 and 58 are energized. The disk 59 is attached to the spindle 9, which carries a series of movable brushes 10. These brushes are adapted to be moved over a series of stationary contacts 11, which contacts are arranged in rows in a semi-cylindrical contact bank. 95 The brushes 10 are normally held out of contact with the stationary contacts 11, and are arranged so that a selected set may be tripped by projections carried by the spindle 73 in order that the selected set may 100 make contact with the stationary contacts during their movement thereover. The spindle 73 is carried by the disk 8, which also carries the toothed wheel 79. The toothed wheel 79 in its rotation acts to vibrate the 105 arm 71 held in contact therewith, by means of spring pressure. The vibration of the arm 71 acts to operate the springs 69 and 70 and to bring the arm 71 in contact with the spring 69. The toothed wheel 79 is provided 110

at its normal position with a depression of greater depth than at any other portion so that when in normal position the arm 71 may contact with the spring 72 for a purpose to be hereafter described. Carried by the spindle 9 on the brush frame is an arm 76 which is pivotally mounted, and is adapted to be vibrated by teeth on the stationary segment 12 over which a roller 83 carried by said arm is adapted to ride. The vibration of the arm 76 first makes contact between the arm and the spring 78, and then breaks the contact between springs 77 and 78. A solenoid 58 surrounds the spindle 73, and a solenoid 14 surrounds the shaft 75. Both of these solenoids are provided with two windings and the arrangement is such that when either of the windings of the solenoid 14 is energized, the disks 59 and 6 will be brought into engagement, and when either of the windings of the solenoid 58 is energized, the disks 7 and 8 are brought into engagement. For a more detailed description of the selector switch, reference may be had to applicant's British patent referred to above.

In addition to the selector and sending devices above described, a circuit changing device which is known as a sequence switch is used. A switch of this character is shown, for instance, in applicant's Patent No. 1,009,080 granted November 21, 1911. Such a sequence switch is shown diagrammatically on the drawing. The switch springs, however, are not shown in their actual arrangement, but are so located as to give a clear arrangement of the circuits. The position in which any of the various contacts 50, 51, 52, etc., are closed, is indicated by numbers placed adjacent to such contacts, each contact being open in all positions except those indicated by such reference numerals, for example, the contact 54 is closed in its lower position in positions 1, 2 and 7 of the sequence switch, and its upper position is positions 3, 4 and 8 of the sequence switch. The motor magnet of such switch is indicated at 57.

The motor magnet 58 which governs the action of the brush selecting spindle 73 is provided with two windings, each of which forms part of a separate exciting circuit. For the sake of convenience, one of these circuits will be termed circuit A, and the other circuit B. Circuit A may be traced as follows: From battery 3, contact 52 of the sequence switch in position 1, line a, back contact of the stop relay 68, armature 82, stepping magnet 67, hook switch 80, line b, left hand winding of the line relay 66, contact spring 53 of the sequence switch in position 1, contact spring 54 of the sequence switch in position 1, upper winding of the motor magnet 58, spring 70, spring 69 to ground. Circuit B may

be traced as follows: from battery 4, right hand winding of the line relay 66, contact spring 55 of the sequence switch in position 1, lower winding of motor magnet 58, arm 71, spring 69 to ground. It will be observed that circuit B is closed only when the roller carried by the arm 71 is riding on a tooth of the wheel 79 for the reason that when the roller rests in a depression between the teeth, the arm 71 does not contact with the spring 69. Also, when the arm 71 is moved outward by a tooth on the wheel 79, the contact between the springs 70 and 69 is broken, thus opening circuit A. The motor magnet 14 of the brush carrying frame is also provided with two windings, each of which is included in a separate and independent circuit which, for the sake of convenience, may be termed circuits C and D. Circuit C may be traced as follows: from battery 3, contact 80 spring 52 of the sequence switch in position 4, line a, back contact of the stop relay 68, armature 82, stepping magnet 67, hook switch 80, line b, left hand winding 66 of the line relay, contact spring 53 of the sequence switch in position 4, contact spring 54 of the sequence switch in position 4, right hand winding of the motor magnet 14, spring 77, spring 78 to ground. Circuit D may be traced as follows: battery 4, right-hand winding of relay 66, contact spring 55 of the sequence switch in position 4, left hand winding of the motor magnet 14, arm 76, spring 78 to ground. It will be observed that circuit D is closed only when the roller 83 rests upon the top or crest of one of the teeth on the interrupter segment 12, as when the roller rests in one of the depressions between the teeth, contact between the arm 76 and the spring 78 is broken, also the contact between the spring 78 and spring 77 is made when the roller 83 rests in a depression, and is broken when the roller 83 rests on the crest of a tooth.

The operation of the system may be stated as follows: The selector switch will be in normal position and hence the arm 71 will rest in a depression on the tooth wheel 79 and the arm 83 will rest in a depression on the spring 64. Therefore, the springs 70 and 69 will be in contact and the springs 77 and 78 will be in contact. When the subscriber removes his receiver from the hook, circuit A as traced above will be closed. This circuit includes the stepping relay, one winding of the line relay 66, one winding of the motor magnet 58 and the springs 70 and 69. Therefore, the line relay and the motor magnet 58 will be energized. The energizing of the line relay will pull up its armature 15 and will close the following circuit for the motor magnet 57 of the sequence switch: battery 4, armature 15, front contact of the line relay, contact spring 56 of the sequence switch in position 1, motor mag.

net 57 to ground. This will energize the motor magnet 57 and drive the sequence switch into its second position. The spindle 73 will also begin to rotate, due to the energization of the motor magnet 58, the upper winding of which will be energized until the arm 71 contacts with the spring 69. As soon, however, as the arm 71 contacts with the spring 69, circuit A as above traced is closed. Included in circuit B are the right hand winding of the line relay 66, lower winding of the magnet 58, arm 71 and spring 69 so that while the breaking of a contact between the springs 70 and 69 opens circuit A, the motor magnet will be energized over the alternative circuit B, and the line relay will also be energized over this circuit and the armature thereof will not fall back. However, the opening of circuit A at the springs 69 and 70 causes the armature of the stepping magnet 67 to fall back, and causes the sending device to be stepped back one step. Inasmuch as circuit B is closed at the arms 71 and 69, regardless of the sending device, whenever the roller carried by the arm 71 is riding on a tooth of the toothed wheel 79, the rotation of the spindle 73 can be stopped only when a roller carried by the arm 71 is located in a depression between the teeth as that is the only position of the lever 71 in which contact is broken between the arms 71 and the spring 69.

The motor magnet 58 will continue to be energized and the spindle 73 will rotate until a sufficient number of impulses have been sent back through the stepping magnet 67 to step the sending device back to a point determined by the set of brushes which it is desired to select, and at such point the stop magnet 68 will operate. The operation of the stop magnet 68 opens circuit A. Circuit B, however, remains closed until the roller carried by the arm 71 rests in a depression, and when this occurs the motor magnet will be deenergized and the spindle will be stopped in a position to select the desired brush. The opening of circuit B by the stop magnet 68 also deenergizes the line relay 66, which closes at its back contact a circuit for the motor magnet 57 of the sequence switch, which may be traced as follows: battery 4, armature 15, back contact of the line relay 66, contact spring 56 of the sequence switch in position 2, motor magnet 57 to ground. This energizes the motor magnet 57 and drives the sequence switch to position 3. The sending device now begins the second stage of its movement and the stop magnet 68 is deenergized, thus closing circuit C above traced. This circuit includes the left hand winding of the line relay 66, right hand winding of the motor magnet 14, springs 77 and 78. This energizes the line relay 66 and motor magnet 14 so that the brush frame begins to move from its normal position. The energization of the line relay 66 closes the following circuit for the sequence switch: battery 4, armature 15, front contact of the line relay 66, spring 56 of the sequence switch in position 3, motor magnet 57 to ground. This drives the sequence switch to its fourth position. As soon as the brush frame moves from its normal position, roller 83 rides up upon a long tooth, thus closing circuit D and maintaining the motor magnet 14 energized while the brush frame moves from its normal position to the first notch in the interrupter segment 12. It is during this movement that the brush tripping spindle 73 trips the selected set of brushes which are then moved over the stationary contacts 11. As soon as the first depression of the interrupter segment 12 is reached, circuit C will be made by the contact of the springs 77 and 78, and thereafter as the roller 83 rides upon the crest of the teeth of the interrupter segment 12, circuit C will be broken and stepping magnet 67 deenergized, and the sender stepped back to its normal position. When the sender reaches the normal position, the stop magnet 68 will be energized, opening circuit C, deenergizing motor magnet 14 when the roller 83 reaches the bottom of a notch corresponding to the terminals that it is desired to select. The brushes will be accurately centered on the desired terminal for the reason that circuit D will be maintained until the roller 83 reaches the bottom of the notch in the interrupter segment 12.

The operation of the relay 68 also deenergizes line relay 66 and closes the following circuit for the sequence switch motor magnet 57: battery 4, armature 15, back contact of line relay 66, contact spring 56 of sequence switch in position 4, motor magnet 57 to ground, thus driving sequence switch to position 5. After the desired set of terminals has been selected and the rotation of the brush frame stopped, the magnet 68 is deenergized and closes the following circuit: battery 5, contact spring 52 of sequence switch in position 5, back contact of relay 68, armature 82, stepping magnet 67, hook switch 80, line relay 66, contact 53 of the sequence switch in position 5 to the other side of battery 5. The line relay 66 is energized over the circuit just traced and closes at its front contact the following circuit for the sequence switch motor magnet: battery 4, armature 15, front contact and line relay 66, contact spring 56 of the sequence switch in position 5, motor magnet 57 to ground, moving the sequence switch to position six. This is the talking position and the calling subscriber is connected to the called subscriber through the selector.

When the conversation is finished, the talking circuit is opened by hanging up the receiver and the line relay 66 is deenergized.

and closes through its back contact the following circuit for the motor magnet of the sequence switch: battery 4, armature 15, back contact of the line relay 66, contact spring 56 of the sequence switch in position 6, motor magnet 57, thus driving the sequence switch to position 7. The sequence switch in its seventh position closes the following circuit: battery 2, contact 50 of the sequence switch 10 in position 7, left hand winding 66 of line relay, contact spring 53 of the sequence switch in position 7, contact spring 54 of sequence switch in position 7, upper winding of the motor magnet 58, springs 69 and 70 15 to ground. The following circuit is also closed by the sequence switch in its seventh position: from battery 4, right hand winding of the line relay 66, contact spring 55 in position 7, lower winding of motor magnet 58, arm 71, spring 69 to ground, this last 20 circuit being closed while the roller carried by the arm 71 is riding upon a tooth of the toothed wheel 79. The spindle 73 will rotate, being energized by first one and then 25 the other of these two circuits just traced, depending upon whether the contact is made by the spring 69 and arm 71 or springs 69 and 70, until it reaches normal position, when the roller carried by the arm 71 will 30 drop into the deep notch.

When the roller carried by the arm 71 drops into the deep notch as described above, the arm 71 makes contact with the spring 72 and closes a circuit for the motor 35 magnet of the sequence switch which may be traced as follows: From battery 4, right hand winding of the line relay 66, contact spring 55 of the sequence switch in position 7, lower winding of magnet 58, arm 71, 40 spring 72, contact spring 51 of the sequence switch in position 7, motor magnet 57 of the sequence switch to ground. This drives the sequence switch to its eighth position and opens the circuit of the motor magnet 58.

In the eighth position of the sequence switch, the following circuits are closed: from battery 2, contact spring 50 of the sequence switch in position 8, left hand winding of the relay 66, contact spring 53 of the sequence switch in position 8, contact spring 54 of the sequence switch in position 8, right hand winding of the motor magnet 14, spring 77, spring 78 to ground; also from 55 battery 4, right hand winding of the relay 66, contact spring 55 of the sequence switch in position 8, left hand winding of the motor magnet 14, arm 76, spring 78 to ground. The motor magnet of the wiper carriage is 60 thus energized from one or the other of these circuits until it is returned to normal position, at which time the roller 83 falls into a depression of the insulated metal segment 64. When this occurs, the following 65 circuit is established: battery 4, right hand

winding of relay 66, contact spring 55 in position 8 of the sequence switch, left hand winding of the motor magnet 14, arm 76, roller 83, insulated metal segment 64, contact spring 51 of the sequence switch in position 8, motor magnet 57 of the sequence switch to ground. This drives the sequence switch into normal position and opens the circuit previously established through the motor magnet 14. This leaves all the mechanism in its normal position and ready for 75 the next call.

Although several batteries have been shown as connected to various parts of the circuits, it is understood that these all may 80 be and preferably are part of the central battery at the central office.

While the system has been described in connection with a selector switch of the type which has been developed by the applicant, 85 obviously the system could be used with any well-known form of selector switch in which motor magnets are used to drive the switch.

Having thus described my invention, 90 what I desire to claim is as follows:

1. In an automatic telephone system, a selector switch comprising stationary contacts and contacts adapted to be moved over said stationary contacts, an electro-responsive 95 device governing the movement of said movable contacts, and means comprising one of a plurality of independent magnetizing windings for said electro-responsive device adapted to prevent said movable contacts 100 from stopping between two adjacent stationary contacts.

2. In an automatic telephone system, a selector switch comprising stationary contacts and contacts adapted to be moved over 105 said stationary contacts, an electromagnet governing the movement of said movable contacts over said stationary contacts, a pair of independent coils for said electromagnet adapted to control the same, a local 110 circuit for one of said coils ineffective except while the movable contacts of the selector switch are intermediate two adjacent stationary contacts.

3. In an automatic telephone system, a 115 selector switch comprising stationary contacts and contacts adapted to be moved over said stationary contacts, an electromagnet governing the movement of said movable contacts over said stationary contacts, a pair 120 of windings for said electromagnet, a main and a local controlling circuit for said windings respectively, and a switch actuated in the movement of said selector switch adapted to shift the control of said electromagnet from said main circuit to said local circuit during that portion of the movement of the selector switch in which the movable contacts are intermediate two adjacent stationary contacts.

4. In an automatic telephone system, a selector switch comprising stationary contacts and contacts adapted to be moved over said stationary contacts, a magnetic clutch for coupling said movable contacts with a source of power, and a plurality of independent windings for said clutch by which said magnetic clutch may be controlled.
5. In an automatic telephone system, a selector switch comprising stationary contacts and contacts adapted to be moved over said stationary contacts, a magnetic clutch for connecting said movable contacts to a source of power, a plurality of independent magnetizing windings for said magnetic clutch, and a switch actuated by the movement of said selector switch for shifting the control of said clutch from one of said windings to another.
6. In an automatic telephone system, a selector switch, a line relay and a controlling device, a circuit including an electro-responsive device associated with said controlling device, an electro-responsive device associated with said selector switch and a winding of said line relay, said circuit adapted to control the movement of said selector switch during a part of its movement, and a local circuit including the electro-responsive device associated with said selector switch and a winding of said line relay controlling the movement of the selector switch during a part of its movement.
7. In an automatic telephone system, the combination of a selector switch and a sending device, each adapted to control and be controlled by the other, a motor magnet having two windings associated with said selector switch, a stepping magnet associated with said sending device, a circuit including said stepping magnet and a winding of said motor magnet, and an additional local circuit including a second winding of said motor magnet.
8. In an automatic telephone system, a selector switch comprising a series of brushes movable over rows of stationary contacts, means movable to select one set of said brushes, an electro-responsive device for operating said brush selecting means, a plurality of independent circuits over which said electro-responsive means is adapted to be controlled, whereby the brush selector can stop only in one of a predetermined number of brush selecting positions.
9. In an automatic telephone system, a selector switch comprising a series of brushes movable over rows of stationary contacts, a rotatable brush selecting spindle associated with said selector switch, a motor magnet for said brush selecting spindle, means comprising a plurality of independent circuits for said motor magnet to prevent the stopping of said spindle except when in one of a plurality of brush selecting positions.
10. In an automatic telephone system, a selector switch comprising a series of brushes movable over rows of stationary contacts, a rotatable brush selecting spindle associated with said selector switch, a motor magnet associated with said brush selecting spindle, a plurality of independent controlling circuits for said motor magnet, and a switch actuated in the movement of the brush selecting spindle for shifting the control of said motor magnet from one of said controlling circuits to another of said controlling circuits.
11. In an automatic telephone system the combination with a sender having a controlling magnet associated therewith; a selector switch having a controlling magnet associated therewith, and an interrupter, said magnets and interrupter being connected in series in the same circuit; of electrical means for preventing said selector switch from stopping between two adjacent contacts.
12. In an automatic telephone system, a circuit including a controlling magnet of a sender, a motor magnet of a selector switch, and an interrupter in series; and means comprising an additional circuit for controlling said motor magnet while said first named circuit is interrupted.
13. In an automatic telephone system the combination of a selector switch and a sender, each adapted to control and be controlled by the other, a motor magnet and an interrupter associated with said selector switch, and a controlling magnet associated with said sender, said motor magnet, controlling magnet and interrupter being connected in series in the same circuit, and electrical means for preventing said selector switch from stopping in any except one of a plurality of definite stopping positions.
14. In an automatic telephone system in combination a sender controlling magnet, a selector switch motor magnet, an interrupter, a circuit changing relay, and a plurality of circuits, one of said circuits including said controlling magnet, said motor magnet, said relay and said interrupter in series, and another circuit including said motor magnet and said relay in series.

Signed at Antwerp, in the Province of Antwerp and Kingdom of Belgium, this 21st day of May, 1913.

FRANK R. McBERTY.
